UNITED STATES PATENT OFFICE.

FRITZ LOWENSTEIN, OF NEW YORK, N. Y.; JOHN C. WAIT, ADMINISTRATOR OF SAID
FRITZ LOWENSTEIN, DECEASED, ASSIGNOR, BY MESNE ASSIGNMENTS, TO RADIO
PATENTS CORPORATION, A DOMESTIC CORPORATION.

METHOD AND APPARATUS FOR MAKING AND BREAKING ELECTRICAL CIRCUITS.

Application filed May 1, 1918. Serial No. 231,840.

This invention relates to methods of and apparatus for making and breaking electrical circuits; and more particularly it relates to closing and opening heavy current circuits through the approach and separation of relatively movable contacts or terminals in such a circuit, such relative movement being very small as compared with that heretofore employed and considered necessary in practice. That is to say, whereas it has been customary heretofore to employ gap openings of an order of magnitude of a thirty-second of an inch or more, the present invention involves the employment of gap openings of only a few thousandths of an inch. Obviously the normal circuit voltage must not be high enough to break down a gap of the small magnitude here in question. In other words, the invention is applicable more particularly to circuits of comparatively low voltage.

In opening circuits carrying relatively heavy currents, much difficulty has been encountered heretofore by reason of the arcing which occurs when such circuits are broken in the usual manner. Not only are the terminals of the commonly employed switches or other circuit-interrupting devices so rapidly pitted and eventually rendered unserviceable as to make frequent replacement necessary, but also there is often considerable danger and inconvenience in operating such devices. The many attempts heretofore made to prevent such arcing or to minimize its effects, have been only partially successful at best and have resulted in no thoroughly satisfactory solution of the problem.

I have discovered that the arcing ordinarily caused by opening a heavy current circuit can be practically eliminated or suppressed to any desired extent by restricting the width of the circuit-breaking gap to a relatively minute distance whose order of magnitude corresponds to a few thousandths of an inch. By this simple expedient the formation of an arc between the relatively movable terminals or contacts where the heavy current circuit is opened may be entirely or largely suppressed; while on the other hand separating said contacts the greater distance required by the prior practice, all other conditions remaining identically the same, produces violent arcing.

No attempt is made here to explain this phenomenon on theoretical grounds, but the established fact is noted as a most important advantage attained in the practice of my invention.

While the principles of the invention are to be understood as of general application, they are of especial utility in the art of radio signaling where the high tension and high frequency impulses or wave trains radiated from the sending station are the ultimate result, through intermediate means, of repeatedly making and breaking a power supply circuit of comparatively high amperage. Accordingly the application of the invention to radio transmission, and especially to radio telegraphy, will be herein-after described by way of a typical concrete embodiment of the broad principles of the invention, without implying thereby any limitation of the invention to such use.

A radio transmitter system of the type commonly used at the present time comprises a power circuit feeding the primary of a power transformer, whose secondary in turn feeds the so-called closed or oscillation circuit, which latter energizes the antenna or radiating circuit. The power circuit is normally open, when the transmitter is not in use, but by intermittently closing said power circuit for periods of varying length corresponding to the dots and dashes of a telegraphic code, the desired oscillations are set up in the closed oscillation circuit and by it transferred to the open or antenna circuit for radiation. An instrument similar in general to the ordinary telegraph sending key is usually employed to make and break the power circuit in the manner described. As the current in the power circuit is relatively heavy, arcing at the make-and-break contacts of the transmitter key has always been a source of constant trouble, and it is in this connection that my invention finds its greatest present utility. By limiting the permissible relative movement of the make-and-break contacts to a very small distance, say from five to ten one-thousandths of an inch, for example, arcing is substantially eliminated. In a typical instance, the voltage of the power circuit may be 200 volts or thereabout, for example.

The new method can be practiced with

circuit-breaking devices of various forms, but the novel form of transmitter key illustrated in the accompanying drawings is especially suitable for radio signaling work and has given excellent results in actual service. In the drawings—

Fig. 1 represents a complete transmitter key in plan;

Fig. 2 is a side elevation of same; and
10 Figs. 3 and 4 are detail vertical and horizontal sections on a larger scale.

Referring to the drawings, the several parts of the key device are mounted on a substantial base 10 of suitable insulating material. Secured to this base are conducting castings 11 and 12. The conductor 11 is a substantially flat strip except at one end where it extends upwardly a short distance, forming a pedestal to support the lower and stationary contact disk 13 which is most desirably made of silver. The other conductor 12, extends upwardly from the base for some distance and then horizontally to form an overhanging supporting bracket. The conductors may be anchored to the insulation base in any suitable manner. In the present instance screws 14 are provided for this purpose, being received in countersinks formed in the under side of the base and extending upwardly to cooperate with nuts 15 to form binding posts for suitably connecting the key in a power circuit. The opposite end of conductor 11 is similarly anchored to the insulating base by a screw 16. 25 After the anchorage screws are in position, the countersinks may be plugged with sealing wax or the like as indicated at 17.

The upper and movable silver contact disk 18 is carried on the operating arm 19, whose bifurcated end 20 embraces the relatively broad upright portion of supporting conductor 12, and is pivotally connected thereto by means of the assembling and pivot pin 21, which is held rigid with member 12 by set screws 22. By thus pivoting member 19 on two fixed bearing points widely spaced apart, any lateral play of said member 19, due to wear in the bearings, is reduced to a minimum. A coiled spring 23 confined between the operating arm and a cupped adjusting nut 24, working on screw 25 mounted in the base, normally presses the operating arm upwardly and tends to separate contacts 13 and 18. The upward movement of the operating arm is limited by stop means of suitable character. In the present example this stop means is of a special design which has been found to be particularly useful with a sending key of this character 50 where the gap or opening between the key contacts in breaking the circuit should be limited to a very small maximum but at the same time should be adjustable below that maximum to a certain extent. To this end, 60 the overhanging arm of member 12, as here

shown, is provided with two stops 26 and 27, of which one, 26, is a screw adapted to be set in fixed position corresponding to the maximum contact opening and is not intended to be adjusted during the operation of the key; 70 while the other stop 27, is formed by a screw which can be set to give any desired gap opening between zero and the maximum permitted by the stop screw 26. The adjustable stop screw 27 may be locked in any desired position by means of thumb nut 28. In the specific example here shown the stop screw 26 performs a double function in that it also cooperates with nut 29 to press one terminal of flexible braided conductor 30 80 firmly into contact with conductor 12, the other terminal of said conductor being similarly held in contact with the operating arm 19, by means of binding screw 31, and nut 32. It is to be noted that the combined stop 85 and binding screw 26 extends loosely through the conductor 12 and occupies its correct position as a permanent stop only when nut 29 is drawn firmly up into good contact with the terminal of the flexible lead 90 30. This construction has certain desirable practical advantages.

In a typical example, the faces of the circular silver contact disks 13 and 18 may be one-half inch to five-eighths inch in diameter, and the fixed stop 26 may permit a maximum gap opening of say 0.015 to 0.020 inch, a distance which may be characterized, for convenience in reference, as corresponding in order of magnitude to a hundredth of an inch. The best operating distance is between 0.005 and 0.010 inch as before stated. Such a key can be used practically indefinitely with circuits carrying as high as 60 amperes, without arcing to an excessive extent; whereas, with transmitter keys of comparable size heretofore in use, operation at higher than about 35 to 40 amperes was accompanied by excessive arcing, and the rapid destruction of the contact members 100 compelled frequent replacement.

What I claim is:

1. A transmitter key comprising the combination, with cooperating relatively movable make-and-break contacts and appropriate operating means therefor, of resilient means tending to separate said contacts, fixed stop means restricting such separation to a maximum distance not substantially exceeding one one-hundredth of an inch, and adjustable stop means for varying the permissible separation between zero and the upper limit.

2. A transmitter key comprising the combination, with cooperating relatively movable make-and-break contacts and appropriate operating means therefor, of resilient means tending to separate said contacts, combined terminal-clamping and stop means restricting such separation to a predetermined 130

mined distance, and adjustable stop means for fine adjustment of the separating distance permitted by the fixed stop.

3. A transmitter key comprising the combination, with cooperating relatively movable make-and-break contacts and appropriate operating means therefor, of resilient means tending to separate said contacts, a movable stop member arranged, when in operative position, to limit the separation of said contacts to a predetermined maximum distance, and at the same time to firmly clamp a conducting lead in place.
4. A transmitter key comprising the combination, with cooperating relatively movable make-and-break contacts and appropriate operating means therefor, of resilient means tending to separate said contacts, a stop screw arranged, when turned down into limiting position, to restrict the separation of said contacts to a distance not substan-

tially exceeding 0.015 to 0.020 inch and a terminal member arranged to be firmly clamped in place by said screw only when the latter is in its limiting position afore-
said.

5. A make-and-break key of the character described, comprising a pair of cooperating contacts, a movable operating arm carrying one of said contacts and having a bifurcated portion, a relatively broad supporting member embraced by said bifurcated portion, an assembling and pivot pin extending through said supporting member and said bifurcated portion of the operating arm to provide spaced pivot bearings therefor, and means for holding said pin rigid with said supporting member.

In testimony whereof I hereunto affix my signature.

FRITZ LOWENSTEIN.
